UNITED STATES PATENT OFFICE

162,030

DECK OF PLAYING CARDS

Don E. Hill and Eugene E. Petersen, Clinton, Iowa

Application July 14, 1949, Serial No. 3,908

Term of patent 3½ years

(Cl. D34—13)

To all whom it may concern:

Be it known that we, Don E. Hill, a citizen of the United States, residing at 422 Sixth Avenue South, city of Clinton, county of Clinton, State of Iowa, and Eugene E. Petersen, a citizen of the United States, residing at 503½ Sixth Avenue South, city of Clinton, county of Clinton, State of Iowa, have invented a new, original, and ornamental Design for a Deck of Playing Cards, of which the following is a specification, reference being had to the accompanying drawings, forming a part hereof.

Figures 1, 2 and 3 are plan views of one suit of our deck of playing cards, showing our new design;

Figures 4, 5 and 6 are plan views of a second suit of the deck of playing cards;

Figures 7, 8 and 9 are plan views of a third suit of the deck of playing cards;

Figures 10, 11 and 12 are plan views of a fourth suit of the deck of playing cards;

Figure 13 is a plan view of the four cards to be used as aces in the deck of cards, and

Figure 14 is a plan view of two cards to be used as jokers in the deck of cards.

The cards in the deck are of no appreciable thickness, and the backs thereof may be plain or conventional.

We claim:

The ornamental design for a deck of playing cards, substantially as shown and described.

DON E. HILL.
EUGENE E. PETERSEN.
